U.S. Appl. No. 13/799,937, filed Mar. 13, 2013, Nelson.

Primary Examiner — Susan Bennett Hattan

Assistant Examiner — Vy Koenig

(74) Attorney, Agent, or Firm — Norton Rose Fulbright US LLP

CLAIM

The ornamental design for a bath transfer bench, as shown and described.

DESCRIPTION

FIG. 1 is a front perspective view of my design comprising a bath transfer bench;

FIG. 2 is a front side orthogonal view of my design;

FIGS. 3 and 4 are left and right side orthogonal views of my design; and,

FIG. 5 is a top orthogonal view of my design.

The dashed lines in the figures represent environmental structure and form no part of the claimed design.
